UNITED STATES PATENT OFFICE
LIQUID FUEL BURNER
1,985,970
Earl E. Behler, Grand Rapids, Mich., assignor to
W. C. Hopson Co., Grand Rapids, Mich.

Application October 3, 1932, Serial No. 635,901

2 Claims. (Cl. 158—37)

The main objects of this invention are:

First, to provide an improved liquid fuel burner supply and overflow system.

Second, to provide means in a system of this character whereby air under pressure may be used to blow out and clear the supply or drain pipe in the event of a stoppage therein.

Third, to provide improved means for taking care of the liquid fuel delivered to the supply pipe in the event of a stoppage in the burner or in the supply pipe.

Fourth, to provide a by-pass connection between the supply pipe and the drain pipe which may be quickly and easily removed so as to provide access for the introduction of air under pressure to either one or both of these pipes.

Fifth, to provide a system of this character that is simple and economical in its parts and efficient and effective in operation.

Objects relating to details and economies of my invention will appear from the description to follow. The invention is defined in the claims.

A structure which is a preferred embodiment of my invention is illustrated in the accompanying drawing, in which:

Fig. 1 is a fragmentary view mainly in side elevation and partially conventionalized, parts being broken away and shown in vertical section, of a system or apparatus embodying the features of my invention.

Fig. 2 is an enlarged fragmentary view in side elevation of the supply pipe coupling with a hand pump connected thereto for supplying air under pressure to clear the drain pipe.

Fig. 3 is a similar view of the supply pipe coupling with a hand pump connected thereto for blowing out the burner supply pipe.

In the embodiment of my invention illustrated 1 represents a brooder stove or heater provided with a burner 2, considerably conventionalized in the illustration. The fuel is supplied to the feed cup 3 by the feed or supply pipe 4 leading from the fuel supply tank 5. The pipe 4 has a feed device designated generally by the numeral 6 and including a feed regulating valve 7 and a thermostat mechanism designated generally by the numeral 8. The feed device is provided with a sight-window 9 so that the amount of fuel being fed can be determined by inspection, drops of fuel being indicated in the drawing.

The burner is provided with a drain pipe 10 leading to a suitable receptacle at the outside of the brooder house 11, the tank 5 being also arranged on the outside of the brooder house. The drain receptacle is not illustrated.

The feed or supply pipe 4 is connected to the drain pipe 10 by means of a by-pass conduit 12. This conduit is connected to the feed pipe 4 by

the coupling 13 arranged at the rear of the regulating valve 7 and to the drain pipe 10 by the coupling 14 arranged in advance of a cut-off valve 20 in the drain pipe. The couplings 13 and 14 have threaded nipples 15 and 16, respectively adapted to receive the threaded coupling members 17 of the by-pass conduit or the chuck or coupling 18 of the air pump 19 as shown in Figs. 2 and 3.

With this arrangement of parts the feed regulating valve 7 and the thermostat are adjusted to properly control the normal supply of fuel to the burner. However, in the event of the fuel feed pipe becoming clogged the fuel will pass through the by-pass 12 to the drain pipe 10, and to clear it the coupling 17 for the by-pass to the nipple 13 is disengaged and the pump 19 connected to the nipple 15 of the coupling 13. The feed pipe ordinarily becomes clogged at or adjacent the burner and with this condition the regulating valve 7 is closed and the feed pipe may be freed from obstacles by means of the pump.

In the event of clogging the drain pipe, which ordinarily occurs at the burner end thereof, the regulating valve 7 is closed and also the drain pipe valve 20, and the coupling 17 for the by-pass passage to the coupling 14 is disconnected and the air pump connected to the nipple 16, and the obstruction may be blown or discharged from the drain pipe. These operations may be quickly and rapidly performed to remove any obstructions and without removing the burner from the heater or the operator having direct access to the burner. This not only results in a great saving of time but has a large factor of safety and avoids the spilling of liquid fuel, which is commonly incident to cleaning systems of this type.

I have illustrated and described my improvements in more or less conventionalized form in an embodiment which I have found highly practical. I have not attempted to illustrate certain modifications which might be desirable to adapt to particular installations as it is believed that this disclosure will enable those skilled in the art to which the invention relates to embody or adapt the same as may be desired.

Having thus described my invention what I claim as new and desire to secure by Letters Patent is:

1. A heating apparatus or system comprising a liquid fuel burner, a gravity fuel feed pipe for said burner including an upright section, a fuel feed regulating valve adapted to cut off the supply of fuel, a gravity drain pipe for said burner provided with a cut-off valve substantially spaced from the burner, and a by-pass connection from the upright section of said fuel feed pipe to said drain pipe opening to the

fuel feed pipe at the rear of said regulating valve and to said drain pipe in advance of its said cut-off valve, the connections for said by-pass to said feed and drain pipes comprising 5 couplings having threaded nipples adapted to detachably receive couplings for said by-pass conduit or the chuck of an air pump.

2. A heating apparatus or system comprising a liquid fuel burner, a gravity fuel feed pipe for 10 said burner including an upright section, a fuel feed regulating valve adapted to cut off the supply of fuel, a gravity drain pipe for said burner

provided with a cut-off valve substantially spaced from the burner, and a by-pass conduit from the upright section of said fuel feed pipe to said drain pipe opening to the fuel feed pipe at the rear of said regulating valve and to said drain pipe in advance of its said cut-off valve, the connections for said by-pass to said feed and drain pipes comprising couplings to which 5 said by-pass is detachably connected and adapted to receive means for delivering air under 10 pressure.

EARL E. BEHLER.
